UNITED STATES PATENT OFFICE.

WILLIAM E. WINE, OF TOLEDO, OHIO.

CAR-DOOR-LOCKING DEVICE.

Application filed January 10, 1922. Serial No. 528,243.

To all whom it may concern:

Be it known that I, WILLIAM E. WINE, a citizen of the United States of America, residing at Toledo, in the county of Lucas 5 and State of Ohio, have invented certain new and useful Improvements in Car-Door-Locking Devices, of which the following is a specification.

My invention relates to new and useful 10 improvements in car door locking devices and especially to a locking device that is designed to hold and lock the drop bottom doors of a freight car.

One of the principal objects of the present 15 invention is to provide a small casting in the form of a housing in which there is located a pivotal arm, a latch member pivoted to said arm and a dog for retaining the pivotal arm and the latch member in 20 their locked position; the casting to be secured to the bottom of the drop bottom door and at one corner thereof, so that the latch member will engage and be supported on a hook which is fastened to the side of the 25 car.

Still another object of the invention is to provide a locking device which will be very compact, relatively strong and readily applied to the drop doors of freight cars.

Still another object is to provide a double faced hook as, in a number of the cars in use today, drop bottom doors are so arranged that the outer ends of the doors when closed will be adjacent, therefore, a double faced hook placed on the side of the car centrally of the inner ends of the door will serve as a supporting means for the two doors, provided, of course, an engaging member for the hook is placed on each of said doors.

In the present embodiment, I have partially shown the adjacent edges of two doors, two locking devices, one being fastened to each door, and a common central plate, and it is to be understood that a similar arrangement will be used on the other side of the car, as the doors are supported at both of their sides.

Of course, if the drop doors are singularly arranged in the car, a single faced plate may 50 be used in each instance rather than a double one as shown in the present embodiment.

With the above objects in view, the invention consists in certain new and novel

arrangements and combination of parts as will be hereinafter more fully described 55 and pointed out in the drawings.

In the drawings showing a preferred form of the invention—

Fig. 1 is a view in elevation showing a fragmentary side portion of a car, a part of 60 two doors, two locks, secured to the inner adjacent edges of the door, one of said locks being partly in section for the sake of clearness.

Fig. 2 is a sectional view taken along line 65 2—2 of Fig. 1.

Fig. 3 is a sectional view taken along line 3—3 of Fig. 1, looking in the direction of the arrow.

Fig. 4 is a vertical view taken on line 70 4—4 of Fig. 1.

In the drawings, a fragmentary portion 1 of the side of a car is shown as well as a portion of two doors 2 and 3, which doors swing upwardly towards each other as 75 clearly shown in Fig. 1.

Both of these doors are provided with transversely extending angle irons 4, each having a leg riveted to the door bottom, these angles extending slightly beyond the 80 sides of the door as shown in Figs. 2 to 4 inclusive.

Other transversely extending members might be used rather than angle irons, but I have found in practice that they are preferable due to their lightness, mode of attachment and strength.

Referring now in particular to the gist of the invention, there is shown in the several views a form of housing 5 which is preferably cast, this housing comprising a top securing plate 6, as shown in the dotted lines in Fig. 2, a small web plate 7 and the main body plate 8 having the depressed portion 9 formed therein, from which extends the 95 short bearings 10 and 11 which are drilled to receive rivets.

The forward end of this housing is provided with a top wall 12, a bottom wall 13, a front wall 14 and an outer wall 15 forming a box like chamber. The front wall 14 having formed therein a slot 16, the edges of which are slightly rounded as at 17 to act as a guide for a latch member which will shortly be described. Formed on the 100 bottom wall 13 and extending from the 105

outer wall 15 to the body plate 8 is a flange 18 which is also slightly rounded to form a resting point for the latch member 20 now to be described. Pivots mounted on the 5 bearing 10 is the short arm 19 to the outer end of which is pivoted the latch 20 which is bifurcated as at 21 while at its outer end a portion is cut out centrally to form the stubs or nibs 22. This latch member 20 10 passes through the slot 16 in the front wall 14 of the housing 5 as heretofore mentioned and is adapted to engage and be supported on a ledge 23 formed on the edge of a plate 24, the two outer stubs 22 passing beyond 15 the edge of the plate directly above the ledge 23, as may be clearly seen in Fig. 2.

Pivots secured to the other bearing 11 is an irregular shaped cam or dog 25 which is provided with a lug 26 for manipulating 20 the same, and extending between the two bearings 10 and 11 is the short plate or strap 27 which holds the arm 19 and the dog 25 on the housing.

The housing 5 in practice is secured to the 25 door by riveting through the plate 6 and through the top wall 12, an offset end portion of the plate 8 allowing the top wall 12 to lie snugly against the angle iron 4.

The locking plate 24 has its opposite edge 30 similarly arranged, that is, with a ledge so that the one plate will suffice for the supporting of the two doors at one side of the car, while a similar arrangement will be provided on the opposite sides of the door 35 and car.

The operation of the lock is exceedingly simple and will be readily understood from the foregoing description. When the door is raised to its closed position, the latch member will rest on the ledge 23 of the plate 24 and the dog will be forced downwardly 40 against the arm 19, thus holding the arm and latch member in their locked position. To release the door, the dog will be swung 45 back and the latch member retracted by forcing its inner pivotal end upwardly as shown in the dotted lines in Fig. 1 so that the latch no longer rests on the ledge of the hook.

50 From the foregoing it will be seen that I have provided a means for supporting and locking the drop doors of a car that is relatively inexpensive to manufacture and made up of but a few parts, which are conveniently housed and in a relatively small space.

Many slight changes may be made without in any way departing from the spirit and scope of the invention.

What I claim as new and desire to secure 60 by Letters Patent is:—

1. In combination with a car having a drop bottom door, a locking device comprising a housing secured to said door, a latch in said housing, an arm pivotally secured to said latch, means associated with 65

said arm for locking the same when said arm and said latch are in their locking position and means secured on the car body for supporting the door through said locking device.

2. A locking device for doors comprising a housing, said housing having a main body plate and a box like portion at the forward end thereof, said box like portion provided with a slot at its front face, a 70 latch extending through said slot, an arm pivotally mounted on said body plate and connecting with said latch, said latch and said arm having a toggle action and a dog secured to said body plate for retaining the 75 latch in its outermost position.

3. A locking device for doors comprising a housing, said housing having a main body plate, a box like section near its forward end, the said box like locking portion provided with a slot, a latch extending through said slot, an arm pivotally secured to the body plate and pivotally secured to the rear end of said latch, the arm and latch having a toggle action, a dog for locking the arm and latch and a top fastening plate formed on said housing.

4. A locking device for doors comprising a housing having a main body plate and a substantial box like chamber, and a 95 flange extending across said chamber, the front wall of said box like chamber provided with a slot therein and a latch extending through said slot, an arm pivotally mounted to the body plate and pivotally secured to 100 said plate, said latch and arm having a toggle action, said latch resting on said flange when in its horizontal positions, and the forward end of said body plate being depressed slightly offset.

5. A locking device for doors, comprising a main body plate, a box like casing formed at the forward end of said body plate and offset with relation to the upper surface of the said body plate, a portion of the body plate being laterally depressed and bearings extending from said depressed portion, the front wall of said casing having a slot therein, a latch extending through said slot, an arm pivotally mounted on one of said 110 bearings and having its outer end pivotally secured to said latch and said latch and said arm having a toggle action, a dog pivotally mounted on the other bearing and a strap extending from the outer end of one bearing to the other to retain the dog and arm on the body plate.

6. A locking device for swinging doors comprising a housing having a main body plate, a box like casing formed at the forward end of said body plate and being offset with relation to the upper main portion of the body plate, said casing having bearings extending from said depressed portion, a dog mounted on one of said bearings, 115 120 125 130

an arm mounted on the other of said bearings and a strap extending from one bearing to the other to hold the said parts in position, a latch pivotally secured to the 5 forward end of said arm, said latch having nibs formed on its outer end, adapted to partly surround a cooperating hasp member, said arm and said latch having a toggle movement and said dog locking said arm 10 in its horizontal position.

7. In combination with a freight car body having drop bottom doors whose outer edges are adjacent when swung to a closed position, a hook secured to the car body 15 and central of the adjacent edges of said door, said hook having oppositely disposed supporting faces, a locking device on the forward portion of said doors and each of said devices comprising, a housing having a latch 20 member adapted when in its outermost position to rest on a face of said hook, means in said housing for retracting the latch and

means for locking the latch in its outward and supporting position.

8. In a door arrangement for railway 25 cars, the combination with the car body of a pair of swinging doors, a locking member attached to the car body near the adjacent edges of the door and having ledges formed at opposite edges thereof, and movable lock- 30 ing members on the doors arranged to engage the said ledges from opposite directions.

9. In a door arrangement for railway cars, the combination with the car body of a door hinged thereto, a movable and a stationary 35 locking member, one being secured to the car body and the other to the door, said members being interengageably arranged for holding the door in closed position, and interengaging means carried by the said 40 members for holding the same against longitudinal displacement.

In testimony whereof I affix my signature.

WILLIAM E. WINE.
